UNITED STATES PATENT OFFICE.

WILHELM FISCHER, OF SEBALDSBRÜCK, GERMANY.

PENCIL-CASE.

SPECIFICATION forming part of Letters Patent No. 613,063, dated October 25, 1898.

Application filed November 19, 1896. Serial No. 612,663. (No model.)

To all whom it may concern:

Be it known that I, WILHELM FISCHER, master molder, residing at Sebaldsbrück, near Bremen, in the German Empire, have invented an Improved Case for Penholders, Pencils, and Similar Articles, of which the following is a specification, reference being had therein to the accompanying drawings.

This invention relates to a case for holding penholders, pencils, and similar articles, the simplicity and practical arrangement of which offers great advantages over those in present use.

In order that my invention may be better understood, I will now proceed to describe the same, reference being had to the accompanying drawings and to the letters marked thereon.

Figure 1 is a plan of the case when open. Fig. 2 shows a sectional view, on a reduced scale, on the line *xx* of Fig. 1; and Fig. 3 shows a sectional view on the line *yy* of Fig. 2.

In a trough-shaped hollow space *a* of the case is pivoted a roller *c*, having several longitudinal grooves *b* on the periphery. One end of the roller *c* extends through the end of the case and is connected with a knob *d* for the rotation of the roller. The longitudinal grooves *b* serve for the reception of the writing utensils to be kept in the case—such as

penholders, pencils, &c.—and as the grooved roller is located by preference in a circular box, Fig. 3, the surrounding wall of the box keeps the articles from falling out as the roller revolves and dispenses with other means for holding the articles in place. In order to facilitate the removal of said utensils from the grooves *b* of the roller *c* and from the case, the roller has a number of recesses or notches *d'*, which correspond to the recesses *f* arranged in the wall *e* over the case.

For the purpose of facilitating the easy opening of the case the cover *g* is provided with a spring and held in locked position by the usual spring-catch or lock. A suitable locking device is shown in the holder *h* and catch *h'*, Fig. 3.

What I claim, and desire to secure by Letters Patent of the United States, is—

In a pencil-holding device, a box or case provided with a hollow space *a*, in combination with a rotating roller *c* pivoted therein, and provided with the longitudinal grooves *b* and the notches *d'* and the recesses *f* in the wall of the case, arranged to correspond with the notches *d'* of the roller, substantially as described.

WILHELM FISCHER.
